OPHTHALMIC MOUNTING

Carl E. H. Colliander, Providence, R. I., assignor
to Lorgnettes, Inc., Providence, R. I., a corpo-
ration of Rhode Island

Application June 7, 1935, Serial No. 25,434

13 Claims. (Cl. 88—41)

The present invention relates to ophthalmic mountings, and more particularly to mountings of the type that are provided with darkened glasses that are adapted to be positioned in front of the lenses of other ophthalmic mountings to reduce the glare of strong sunlight, or the like.

An object of the present invention is to reduce the cost of manufacture of ophthalmic mountings of the above-described character without detracting from their efficiency and utility.

Another object is to provide a novel joint for a split, lens-holding rim.

Another object is to provide a novel connection between a lens-holding rim and a bridge.

Other and further objects will be explained hereinafter in connection with the accompanying drawing, in which Fig. 1 is a perspective of an ophthalmic mounting embodying the present invention; Fig. 2 is a fragmentary perspective, upon a larger scale, of the bridge thereof; Fig. 3 is a corresponding fragmentary perspective of the portion of a rim to which the bridge is adapted to be secured; Fig. 4 is a fragmentary perspective, upon a still larger scale, showing the bridge and rim parts of Figs. 2 and 3 secured to each other, with a lens in the rim; Fig. 5 is a vertical section taken upon the line 5—5 of Fig. 4, looking in the direction of the arrows; Figs. 6 and 7 are fragmentary perspectives corresponding to Figs. 2 and 3, respectively, of modifications; Fig. 8 is a section corresponding to Fig. 5 of the modifications shown in Figs. 6 and 7, with the parts assembled; and Figs. 9 and 10 are fragmentary perspectives corresponding to Figs. 2 and 3 of a preferred embodiment of the present invention.

The ophthalmic mounting of the present invention comprises two rims 2 connected by a spring bridge 4. Each rim is split at its point of junction with the bridge, as shown at 6, the split ends of the bridge being shown at 8 and 10. The split ends 8 and 10 of each rim 2 are locked together and to an end of the bridge 4 by means of cooperating locking elements. As shown in Figs. 1 to 5, 9 and 10, these locking elements may comprise two adjacently disposed slots or other apertures 12 and 14 in an end of the bridge 4 and two pairs 16 and 18 or 17 and 19 of tongues or other projections on the split ends 8 and 10 of the rim. The two tongues 16 or 17, disposed opposite to each other, or unspaced along the periphery of the rim, are disposed in the slot 12 and tightly engaging the walls thereof. The two similarly disposed tongues 18 or 19 are similarly disposed in the slot 14 and similarly engage the walls there-

of. The tongues 16, 17 or 18, 19 of each pair are then bent away from each other, in opposite directions transversely of the rim, and over against the bridge 4, as shown more particularly in Figs. 4 and 5. If desired, however, the pair 20 and 22 of tongues may be adjacently disposed on the bridge and the slots 24 and 26 in which they are disposed on the rim and against the walls of which they tightly engage, as shown in Figs. 6 to 8. The bent-over portions of the tongues will then be concealed, as shown at 28 in Fig. 8, instead of exposed, as shown in Figs. 4 and 5. It will be understood that the tongues 20 and 22 may be disposed on the bridge 4 at right angles to the positions illustrated, as in Fig. 10, so that the tongues 20 and 22, like the tongues 17 and 19, will be spaced from each other along the periphery of the rim. The tongues 20 and 22, like the tongues 17 and 19, would then be bent away from each other in the opposite directions of curvature of the rim and over against the slotted member 2, instead of, as in Figs. 9 and 10, against the slotted member 4.

As the ends of the bridge 4 are positioned against the exterior surfaces of the rims, it is desirable to round them over in cross section, as illustrated at 30, to conform to the surfaces of the rims. Furthermore, as the split ends 8 and 10 of the rims 2 are permanently secured together when joined to the ends of the bridge 4, this would prevent the insertion, in the lens-receiving groove 29, of glasses 31, which are usually smoked or colored. The rims are, therefore, each provided with a bendable or adjustable loop 32, originally occupying the dotted-line positions illustrated at 33 in Fig. 1. After a glass 31 has been inserted in the rim, the arms 34 and 36 of the loop 32 are closed in against each other, from the dotted-line positions to the full-line positions shown at the left of Fig. 1, thereby closing the rim over against the glass 31 in the rim. The loop 32 then serves the further function of a handle with which to manipulate the ophthalmic mounting.

In operation, the loops 32 are grasped between the fingers and thumbs of one's hands, and the rims 2 are moved away from each other, in opposition to the spring action of the bridge 4. The ophthalmic mounting is then positioned in front of one's spectacles upon the face, with the glasses 31 in front of the spectacle lenses. The spring bridge 4 is now allowed to actuate the rims 2 towards each other until the tongues 38 engage against the lower sides of the spectacle rims (not shown). The ophthalmic mounting will be held

in place on the spectacles by the inherent resiliency of the spring bridge 4.

Other modifications will occur to persons skilled in the art and all such are considered to 5 fall within the spirit and scope of the invention, as defined in the appended claims.

What is claimed is:

1. An ophthalmic mounting comprising two members one of which is a split, lens-holding 10 rim, the ends of the rim and the other member being provided with cooperating locking elements for locking the ends of the rim together and for locking the rim to said other member, the locking elements on one of the members 15 comprising two adjacently disposed apertures and the locking elements on the other member comprising two pairs of projections, one of the pairs of projections being disposed in one of the apertures and the other pair of projections being 20 disposed in the other aperture, the projections of each pair being bent away from each other and over against the apertured member.

2. An ophthalmic mounting comprising two members, namely, a split, lens-holding rim and 25 a bridge, means for securing one of the ends of the bridge to one of the ends of the rim, the other end of the rim and the said end of the bridge being provided with cooperating locking elements for locking the ends of the rim together and for locking the said other end of the rim to the bridge, one of the locking elements on one of the members comprising an aperture, and one of the locking elements on the other member comprising 30 a projection, the projection being disposed in 35 the aperture.

3. An ophthalmic mounting comprising two members, namely, a split, lens-holding rim and a bridge, the ends of the rim and an end of the bridge being provided with cooperating locking 40 elements for locking the ends of the rim together and for locking the rim to the bridge, the locking elements on one of the members comprising two adjacently disposed apertures and the locking elements on the other member comprising two 45 pairs of projections, one of the pairs of projections being disposed in one of the apertures and the other pair of projections being disposed in the other aperture, the projections of each pair being bent away from each other and over 50 against the apertured member.

4. An ophthalmic mounting comprising a split, lens-holding rim and a bridge, the ends of the rim being each provided with a pair of projections, an end of the bridge being provided with 55 two adjacently disposed apertures, one of the pairs of projections being disposed in one of the apertures and the other pair of projections being disposed in the other aperture and the projections of each pair being bent away from each other and over against the bridge.

5. An ophthalmic mounting comprising two members, namely, a split, lens-holding rim and a bridge, the ends of the rim and an end of the bridge being provided with cooperating locking 65 elements for locking the ends of the rim together and for locking the rim to the bridge, the locking elements on one of the members comprising two adjacently disposed apertures and the locking elements on the other member comprising two 70 pairs of projections, one of the pairs of projections being disposed in one of the apertures and the other pair of projections being disposed in the other aperture, the projections of each pair being bent away from each other and over against 75 the apertured member, the said end of the bridge

being positioned against the exterior surface of the rim and being rounded in cross section to conform to the said surface of the rim.

6. An ophthalmic mounting comprising a split, lens-holding rim and a bridge, the ends of the rim being each provided with an aperture, an end of the bridge being provided with two adjacently disposed pairs of projections, one of the pairs of projections being disposed in one of the apertures and the other pair of projections being disposed in the other aperture, and projections of each pair being bent away from each other and over against the rim.

7. An ophthalmic mounting comprising a split, lens-holding rim and a bridge, and common 15 means for locking the ends of the rim permanently together and for locking the rim permanently to the bridge, the rim having a bendable loop that is adapted to be adjusted to close the rim over against a lens in the rim without destroying the permanent connection of the ends of the rim or the permanent connection of the rim to the bridge, the adjusted loop being adapted to serve as a handle for the ophthalmic mounting.

8. An ophthalmic mounting comprising two 25 members one of which is a split, lens-holding rim, the ends of the rim and the other member being provided with cooperating locking elements for locking the ends of the rim together and for locking the rim to said other member, the locking elements on one of the members comprising two adjacently disposed apertures and the locking elements on the other member comprising two pairs of projections, the projections being spaced from 30 each other along the periphery of the rim, one of the pairs of projections being disposed in one of the apertures and the other pair of projections being disposed in the other aperture, the projections of each pair being bent away from each other in the opposite directions of curvature of 35 the rim and over against the apertured member.

9. An ophthalmic mounting comprising two members one of which is a split, lens-holding rim, the ends of the rim and the other member being provided with cooperating locking elements for 45 locking the ends of the rim together and for locking the rim to said other member, the locking elements on one of the members comprising two adjacently disposed apertures and the locking elements on the other member comprising two pairs 50 of projections, one of the pairs of projections being spaced from the other pair of projections along the periphery of the rim, the projections of each pair being disposed opposite to each other but unspaced along the periphery of the rim, one 55 of the pair of projections being disposed in one of the apertures and the other pair of projections being disposed in the other aperture, the projections of each pair being bent away from each other in opposite directions transversely of the 60 rim and over against the apertured member.

10. An ophthalmic mounting comprising a split, lens-holding rim and a bridge, means for securing one of the ends of the bridge to one of the ends of the rim, and means for securing the said 65 end of the bridge to the other end of the rim, the last-named means comprising an aperture in the said end of the bridge and a projection on the said other end of the rim.

11. An ophthalmic mounting comprising a split, 70 lens-holding rim and a bridge, means for securing one of the ends of the bridge to one of the ends of the rim, the said end of the bridge being provided with an aperture, and the other end of the rim being provided with a projection, the pro- 75

jection being disposed in the aperture and being bent away to lock the said other end of the rim to the said other end of the bridge.

12. An ophthalmic mounting comprising two members, namely, a split, lens-holding rim and a bridge, the ends of the rim and an end of the bridge being provided with cooperating locking elements for locking the ends of the rim together and for locking the rim to the bridge, the locking elements comprising aperture means on one of the members and two projections on the other member disposed in the aperture means and

tightly engaging the walls of the aperture means.

13. An ophthalmic mounting comprising a split, lens-holding rim and a bridge, the ends of the rim and an end of the bridge being provided with cooperating locking elements for locking the ends of the rim together and for locking the rim to the bridge, the locking elements comprising two apertures in the said end of the bridge and a projection on each end of the rim disposed in the respective apertures and tightly engaging the walls of the apertures.
